UNITED STATES PATENT OFFICE.

CARL M. BALDWIN, OF COLUMBUS, OHIO.

DESIGN FOR CANDY OR SIMILAR ARTICLE.

Application filed March 31, 1927. Serial No. 21 415. Term of patent 14 years.

To all whom it may concern:

Be it known that I, CARL M. BALDWIN, a citizen of the United States, residing at Columbus, county of Franklin, and State of Ohio, have invented a new, original, and ornamental Design for Candy or Similar Article, of which the following is a specification, reference being had to the accompanying drawing, forming a part hereof.

I claim:

The ornamental design for candy or similar article as shown.

CARL M. BALDWIN.
